11 Claims. (Cl. 260—290)

1

This invention relates to the resolution of mixtures of 3-picoline, 4-picoline and 2,6-lutidine, particularly to the separation of 3-picoline from said mixtures.

The picolines and other homologs of pyridine are customarily extracted along with other nitrogen bases from coke oven distillates and other sources of heterocyclic nitrogen bases by means of an aqueous solution of mineral acid, usually sulfuric acid. After liberation from these acid solutions by means of alkali, the base mixtures thus obtained are customarily fractionally distilled to obtain fractions predominating in a particular base. Bases such as pyridine, boiling point 116° C., and 2-picoline, boiling point 129.4° C., can generally be obtained in reasonably pure form by fractional distillation, but for the most part the remaining compounds cannot be separated by ordinary distillation methods alone. Instead, the fractions obtained, even when they are of relatively narrow boiling range, contain increasing numbers of pyridine homologs and their isomers. Mixtures of this kind have found limited practical application, mainly as special solvents, and are of relatively low economic value. The individual bases in pure form, however, are products of considerable commercial interest, being useful, for example, in the preparation of pharmaceutical products and dyes. The purity requirements in these fields are quite rigid.

3-picoline, which is found in fractions boiling predominantly within the range 140°–145° C., is of especially high potential value. Nicotinic acid, for example, a member of the vitamin B complex, may be obtained by oxidation of 3-picoline. When mixtures of heterocyclic nitrogen compounds are recovered from sources such as coal tar, the fractions taken within the range 140°–145° C., even closely cut fractions within this boiling range, in general contain as components three pyridine homologs of substantially the same boiling point in roughly equal proportions; i. e., 2,6-lutidine, boiling point 143.8° C., 3-picoline (beta-picoline), boiling point 143.8° C., and 4-picoline (gamma-picoline), boiling point 144.8° C. Derivatives of these compounds are becoming of increasingly greater importance as pharmaceuticals and agricultural chemicals.

Since the three components making up the usual nitrogen base fractions boiling within the range 140°–145° C. (2,6-lutidine, 3-picoline, and 4-picoline) have substantially the same boiling points, fractional distillation is obviously unsatisfactory as a means for resolving the mixtures. Other methods of resolving such mixtures here-

2

tofore disclosed in the published prior art have been generally unsatisfactory in regard to production yields and production costs. Such other methods have usually depended upon fractional crystallization of the more common salts of the bases present, e. g., the sulfates, oxalates, chlorates, picrates, ferro-cyanides and the like. Isolation or purification of individual bases by such methods has been found to be extremely cumbersome and generally insufficiently sharp to obtain compounds of a purity demanded in industry. These methods also have often presented other drawbacks such as prohibitive cost, explosion hazards, and toxicity.

10 It is an object of this invention to provide a commercially feasible process for resolving nitrogen base fractions which contain 2,6-lutidine, 3-picoline, and 4-picoline in substantial proportions, particularly tar base fractions boiling in the range 140°–145° C. containing these constituents in roughly equal proportions.

15 It is a further object of this invention to provide a process for separating substantially pure 3-picoline or 3-picoline-enriched fractions from mixtures thereof with closely related nitrogen bases such as 2,6-lutidine and 4-picoline not readily separable therefrom by distillation.

20 I have discovered that substantially pure 3-picoline or 3-picoline-enriched fractions may be recovered in substantial proportions from mixtures containing 3-picoline, 4-picoline, and 2,6-lutidine by precipitating all or the major part of the 2,6-lutidine and 4-picoline from such mixtures in the form of their hydrochlorides. I have found that the hydrochlorides of 2,6-lutidine and 4-picoline are substantially insoluble in the 3-picoline with which they are associated in close boiling fractions, and are also substantially insoluble in hydrocarbon solvents of the aromatic, naphthenic, or aliphatic types. My invention also comprises a process in which a tar base mixture is first fractionated to obtain a fraction boiling predominantly in the range 140°–145° C. containing substantial proportions of 2,6-lutidine, 3-picoline and 4-picoline, and the bulk of the 2,6-lutidine and 4-picoline is then separated from this fraction in the form of their hydrochlorides.

25 In the process of my invention, the bulk of the 2,6-lutidine and 4-picoline may be precipitated in one step as a hydrochloride mixture, leaving the 3-picoline, or, alternatively, the 2,6-lutidine and 4-picoline may be precipitated in successive steps in the form of their hydrochlorides. Thus I have found that 2,6-lutidine hydrochloride is precipitated preferentially with respect to either of the

picoline hydrochlorides, and 4-picoline hydrochloride is then precipitated preferentially with respect to 3-picoline hydrochloride.

In a preferred method of carrying out the process of my invention, a commercial picoline-lutidine fraction, suitably a tar base fraction boiling predominantly within the range of 140°-145° C. and containing roughly equal proportions of 3-picoline, 4-picoline, and 2,6-lutidine, may be treated with gaseous hydrogen chloride, for example the hydrogen chloride gas obtained commercially from the reaction of sodium chloride with sodium bisulfate or as a by-product in the commercial chlorination of hydrocarbons such as benzene. This hydrogen chloride gas may be added to the three-component mixture of bases or to solutions of the bases in a solvent such as benzene, toluene or paraffinic hydrocarbons. Heat evolved in the ensuing reaction between bases and hydrogen chloride is removed by external cooling. Instead of gaseous hydrogen chloride, the base mixture may alternatively be treated with an aqueous hydrochloric acid which may advantageously be the inexpensive and readily available technical grade of muriatic acid. The term "hydrogen chloride" is used herein to include both gaseous hydrogen chloride and hydrochloric acid. This treatment may be carried out without any diluent present, but is preferably carried out in the presence either of 3-picoline concentrate from a previous run or an inexpensive hydrocarbon solvent such as benzene, toluene, or a paraffinic or naphthenic petroleum solvent.

An amount of hydrogen chloride exactly sufficient to react with the 2,6-lutidine and 4-picoline may be employed. A mixed precipitate of 2,6-lutidine hydrochloride and 4-picoline hydrochloride is thus obtained. However, the precipitation of these hydrochlorides may be carried out in two stages, in the first of which a little less hydrogen chloride than the molar equivalent of 2,6-lutidine present in the mixture is employed. In this case, especially pure 2,6-lutidine hydrochloride is precipitated in the first stage and may be separated by filtration. 2,6-lutidine of substantially 100% purity has thus been obtained. Application of additional hydrogen chloride thereafter in a second stage in amount equivalent to the 4-picoline and 2,6-lutidine remaining in the base mixture leads to precipitation of a mixture of base hydrochlorides in which 4-picoline hydrochloride greatly predominates, concentrations of 85%-90% being obtainable. A fixed small ratio of 2,6-lutidine is simultaneously precipitated, its concentration in the liberated bases from the second hydrochloride precipitate being about 4%. By proper limitation of hydrogen chloride, precipitation of 3-picoline can be avoided.

The reaction of the bases with hydrogen chloride may be carried out at whatever temperature is convenient, e. g., the normally prevailing temperature. When an aqueous hydrochloric acid is employed, the mixture is heated to refluxing temperature, preferably in the presence of a diluent such as 3-picoline concentrate from a previous run to remove the water by azeotropic distillation. The distillate is condensed in a side arm trap where it separates into a water layer and an oil layer. The water layer is removed while the oil layer containing unreacted base and diluent, where such has been used, is continuously returned to the still. When all, or nearly all, of the water has thus been removed, the still

charge is cooled to normally prevailing temperatures to bring about or complete crystallization of the hydrochloride.

The precipitated crystals are isolated by filtration, e. g., by centrifuging, and are freed from adhering 3-picoline mother liquor by washing with a hydrocarbon solvent, e. g., the same hydrocarbon used as diluent for the precipitation. The crystals may be freed from the adhering solvent by drying or other means. Depending upon whether the hydrochloride precipitation was carried out in one step or two steps, either a mixed 2,6-lutidine hydrochloride and 4-picoline hydrochloride product or separate products such as pure 2,6-lutidine hydrochloride and a fraction greatly enriched in 4-picoline hydrochloride are thus obtained. In either case, the nitrogen base is liberated from the crystals thus obtained, for example by adding an equivalent weight of alkali to an aqueous solution of the base hydrochloride. The liberated base which separates out from the resulting salt solution is dehydrated (for example, by treating with solid caustic soda) and distilled.

25 The mother and wash liquors may be distilled to recover solvent for reuse in the process, and to recover the residual 3-picoline concentrate. Where the precipitation is carried out with a carefully controlled amount of hydrogen chloride as above indicated, and equilibrium conditions at ordinary temperatures are approached, the mother liquor will have approximately the following composition: 3-picoline, 86%, 4-picoline, 10%, and 2,6-lutidine, 4%. In actual operation, 35 a 3-picoline concentrate containing from 75%-86% 3-picoline may be obtained. Other heterocyclic bases which may have been present in small amounts in the original base mixture, such as 2-picoline and 2,4-lutidine, also remain in the 40 3-picoline concentrate. This concentrate has a sufficiently high 3-picoline content so that it may be utilized as such in the production of derivatives, such as oxidation to nicotinic acid. If pure 3-picoline is desired, however, it may be obtained in excellent yields by precipitation as 45 phosphate from an alcoholic solution, in accordance with the process of my copending application Serial No. 346,347, filed July 19, 1940.

Where the production of a 3-picoline concentrate is the more important object of the process, precipitation of the 2,6-lutidine and 4-picoline hydrochlorides is preferably carried out as above described in a single operation. In such a case, the mass of precipitate may be disproportionately bulky in relation to the quantity of mother liquor, and the use of a diluent such as a hydrocarbon solvent of coal tar or petroleum origin is particularly advantageous. The handling of a bulky precipitate may also be avoided by carrying out the precipitation of hydrochloride in a plurality of stages. When the production of pure 2,6-lutidine is not important, the amount of hydrogen chloride added in the preliminary stages in multi-stage precipitation is a matter of convenience. In the final stage, however, an amount of hydrogen chloride should be added such that the total hydrogen chloride used is equivalent as accurately as this can be calculated to the 2,6-lutidine and 4-picoline in the base mixture.

Where the precipitation of the hydrochlorides occurs from a hot solution, as in the above process where hydrochloric acid is used for the precipitation and the reaction mixture is refluxed to remove water, I have found it is preferable to

avoid or hold to a minimum the use of hydrocarbon oils as diluents, at least in the initial crystallization stages, since the base hydrochlorides in precipitating from a hot hydrocarbon solution tend to form undesirably large masses, lumps, or pebbles of solids while the crystals which form in hot 3-picoline mother liquor alone are small and granular and easily handled. Preferably, therefore, 3-picoline concentrate from a preceding run is used as diluent, at least in the initial stages of precipitation where the precipitation occurs in a hot solution. After precipitation is complete or is well along, however, hydrocarbon diluents may be added for ease in handling a bulky precipitate.

I have found it is desirable, when using hydrochloric acid for the precipitation, to dehydrate the charge as thoroughly as possible, a small residual percentage of moisture altering the solubility characteristics of the hydrochlorides which it is desired to precipitate, particularly the 4-picoline hydrochloride. A moisture content greater than about 1.5% in the mother liquor is undesirable. I have also found it is undesirable, for the same reason, to have an appreciable amount of a lower alcohol, such as ethanol or methanol, present in the reaction mixture.

The process of my invention may advantageously be applied in the resolution of heterocyclic nitrogen compound mixtures obtained from coke oven distillates, cracked petroleum, shale tar, bone oils, and from other natural as well as synthetic sources of these base mixtures containing substantial amounts of 3-picoline and other nitrogen bases not readily separable therefrom by distillation, e. g., 4-picoline and 2,6-lutidine. As above pointed out, in carrying out the process of my invention, such a mixture is advantageously first subjected to fractional distillation whereby a close cut fraction containing predominantly the 3-picoline and other close boiling compounds is obtained.

The following examples are illustrative of the process of my invention:

Example 1.—Resolution of a 2,6-lutidine-3-picoline-4-picoline fraction involving isolation of pure 2,6-lutidine

The apparatus used consisted of an acid-resistant reaction vessel, provided with agitator, heating and cooling jacket, and with a reflux condenser. Distillation condensate did not immediately return to the vessel, but was collected in a small settling trap, from which condensed liquids could be withdrawn, if desired, or returned to the vessel.

The reaction vessel was charged with 500 parts by weight of a mixture of heterocyclic bases, having a boiling range (bulb distillation) of 142.5-145.0° C. It had approximately the following composition: 2,6-lutidine, 28%; 3-picoline, 34%; 4-picoline, 36%; and, in addition, from 0.5 to 1% each of 2-picoline and of 2,4-lutidine. The agitated bases were gradually mixed with 120 parts by weight of hydrochloric acid of 35% concentration, containing 1.17 molar weight equivalents of hydrogen chloride as against 1.32 molar equivalents of 2,6-lutidine present in the mixture of bases. Sixty parts by weight of toluene were added next. The completed charge was heated to refluxing. The condensate was trapped, allowing it to separate in two layers. The upper layer consisting of a mixture of toluene and heterocyclic bases was continuously returned to the distillation charge, 75

whereas the lower water layer was intermittently withdrawn. The operation was continued until no appreciable quantity of water separated in the trap, a total of 82 volume parts of aqueous layer having been collected.

5 Granular crystals of 2,6-lutidine hydrochloride separated on cooling the charge to room temperature. The resulting slurry was centrifuged and the crystals washed with a small quantity of toluene. Crystals were dried at 90° C., 160 parts of dry material being obtained. The crystals melted at 238° C., corrected—the same melting point as determined for the pure compound. They contained 115 parts by weight of 2,6-lutidine, corresponding to a yield of 82% of the lutidine originally present in the mixture of bases.

20 Crystals were dissolved in water and 2,6-lutidine liberated by addition of an aqueous solution containing 45 parts of sodium hydroxide. The amount of water used in this liberation was so adjusted as to obtain an approximately saturated solution of sodium chloride. The bulk of the liberated lutidine in that case separates as an upper layer which is decanted. A small additional quantity of lutidine may be obtained by partial distillation of the aqueous salt solution. A small quantity of condensate containing water and 2,6-lutidine is again saturated with sodium 25 chloride to recover the remainder of the base. The combined yield of base is completely dehydrated and distilled. The material consists of 30 pure 2,6-lutidine.

35 The toluene-base mixture recovered as mother liquor from the above crystallization was subjected to a further partial precipitation of base as hydrochlorides in accordance with the process more particularly described in the next example for the purpose of resolving the bases present into 40 (a) a precipitated hydrochloride fraction greatly enriched in 4-picoline and (b) a residual fraction of free or uncombined bases greatly enriched in 3-picoline.

Example 2.—Separation of 2,6-lutidine and 4-picoline successively from a 3-picoline-4-picoline-2,6-lutidine fraction

45 In a procedure practically identical with that just described, the same mixture of heterocyclic bases used in Example 1 was caused to react with a slightly increased proportion of hydrogen chloride. Bases obtained from the crystalline precipitate in this case contained: 2,6-lutidine, 90%; 3-picoline, trace; 4-picoline, 9%. The mother liquor, combined with toluene used in washing the crystals, contained approximately 30% by weight of toluene, 68% by weight of free bases, the remaining 2% consisting of dissolved hydrochlorides of bases and water. A sample of the 50 total bases present in this mixture was analyzed and found to contain the following components: 2,6-lutidine, 4%; 3-picoline, 52%; 4-picoline, 42%. In addition, from 1% to 2% of 2-picoline and 2,4-lutidine were present.

55 The reaction vessel of the preceding example was charged with 1700 parts by weight of the toluene-base mixture just described, and 515 parts by weight of hydrochloric acid, technical grade, of 32% concentration, were added. The 60 charge was heated to refluxing until practically all water, 350 parts, had been removed through the trap arrangement. Approximately 290 parts by weight of toluene were taken off by fractional distillation. The remaining charge was gradually 65 cooled to room temperature; a heavy mass of

fine crystals consisting predominantly of 4-picoline hydrochloride separated out. The crystals were isolated by centrifuging and washed with toluene recovered from the vessel charge by fractional distillation. Freed from toluene by drying, these crystals amounted to 605 parts by weight. These crystals were fairly hygroscopic and contained a little absorbed moisture.

Bases were isolated from these crystals by addition of an aqueous solution of sodium hydroxide. The completely dried and distilled bases, 410 parts by weight, had the following composition: 2,6-lutidine, 4%; 3-picoline, 8%; 4-picoline, 88%.

The mother liquor obtained from the crystals, combined with toluene used in washing operations, was agitated with a small quantity of sodium hydroxide solution of 30% concentration to neutralize traces of hydrogen chloride dissolved in the liquor. The aqueous wash solution was drawn off as a lower layer. The upper layer, i. e., the washed toluene, was fractionally distilled in an iron still until toluene had been taken off. The still residue was then distilled with full forward flow, 665 parts by weight of bases enriched in 3-picoline being obtained. The composition of this material was as follows: 2,6-lutidine, 4%; 3-picoline, 76%; 4-picoline, 15%. In addition, the material contained 2-picoline and 2,4-lutidine.

Example 3.—Separation of 2,6-lutidine and 4-picoline simultaneously from a 3-picoline-4-picoline-2,6-lutidine fraction

The mixture of bases described in the first example, 1000 parts by weight, was charged in the reaction vessel previously described, together with 80 parts by weight of toluene and 700 parts by weight of concentrated hydrochloric acid of 35% strength. Water was removed by refluxing the charge and withdrawal of the water through a separating trap. The dehydrated charge was mixed with 380 parts by weight of a mixture of bases having the following composition: 2,6-lutidine, 4%; 3-picoline, 74%; 4-picoline, 20%; from 1% to 2% of 2-picoline and 2,4-lutidine being present in addition to the three main components.

The mixture was agitated and gradually cooled to 25° C. A heavy mass of crystals separated out during the cooling operation. Crystals were centrifuged and washed with toluene to free them from mother liquor, 899 parts by weight, free of toluene, being obtained. Bases liberated from the crystals by customary procedure amounted to 656 parts by weight and had the following composition: 2,6-lutidine, 40%; 3-picoline, 3.5%; 4-picoline, 56%. The mother liquor obtained from the crystals, together with toluene solutions recovered from washing operations, approximately 1250 parts by weight, were washed with a solution containing 50 parts by weight of a 30% solution of sodium hydroxide. The upper layer, i. e., the washed toluene, was fractionally distilled to remove toluene. The residual bases were distilled with full forward flow. Including bases contained in a small intermediate fraction, a total of 701 parts by weight of a fraction rich in 3-picoline were thus obtained. The distilled bases had the following composition: 2,6-lutidine, 4%; 3-picoline, 82.5%; 4-picoline, 12%; traces of 2-picoline and 2,4-lutidine were present.

In a continuous production, one-half of this material may be reused as a diluent in a subsequent crystallization procedure, while the other half is withdrawn as product. Preferably, how-

ever, runs which result in a residual product of high 3-picoline content, i. e., 83%–85% 3-picoline, are selected for withdrawal as product, while runs that result in a residual 3-picoline concentrate of lower concentration are retained separately for use as diluent in subsequent runs.

3-picoline concentrates obtained as in the above examples may be worked up further for isolation of pure 3-picoline in the form of its phosphate, according to the procedure of my copending application Serial No. 346,347. In carrying out such a process, the 3-picoline concentrate may be mixed with toluene and with 70% phosphoric acid, 1 molar equivalent of H_3PO_4 being used for every equivalent of 3-picoline present. The mixture is agitated and brought to refluxing to remove all water present by azeotropic distillation and trapping of the condensate. The dehydrated charge, while still warm, is diluted with methanol and cooled to 20° C. to precipitate 3-picoline phosphate. Crystals produced in this manner are coarser and more easily filterable.

The crystal slurry is centrifuged and washed with methanol at 20° C. The crystals are then dried directly in the centrifuge by blowing with a blast of air preheated to about 80° C. The 3-picoline phosphate crystals thus obtained are dissolved in water and 3-picoline liberated by addition of sodium hydroxide. 3-picoline of 97% to 100% purity may thus be obtained.

Since certain changes may be made in carrying out the above process without departing from the scope of the invention, it is intended that all matter contained in the above description shall be interpreted as illustrative and not in a limiting sense.

What is claimed is:

1. A process for resolving a mixture containing substantial proportions of 3-picoline, 4-picoline, and 2,6-lutidine, comprising reacting said base mixture with an amount of hydrogen chloride just sufficient to react substantially completely with the 2,6-lutidine and 4-picoline, in the presence of a diluent selected from the group hydrocarbon solvents and 3-picoline concentrates, to precipitate 2,6-lutidine and 4-picoline from such mixture in the form of their hydrochlorides.

2. In a process for the production of a 3-picoline concentrate from a mixture containing substantial proportions of 2,6-lutidine, 3-picoline, and 4-picoline, the steps which comprise precipitating hydrochlorides of the 2,6-lutidine and the 4-picoline and separating the uncombined base, enriched in 3-picoline, from said hydrochlorides.

3. In a process for the production of a 3-picoline concentrate from a mixture containing substantial proportions of 2,6-lutidine, 3-picoline and 4-picoline, the steps which comprise reacting said base mixture with an amount of hydrogen chloride just sufficient to react substantially completely with the 2,6-lutidine and 4-picoline, in the presence of a diluent selected from the group hydrocarbon solvents and 3-picoline concentrates, to precipitate hydrochlorides of the 2,6-lutidine and the 4-picoline, and separating the uncombined base, enriched in 3-picoline, from said hydrochlorides.

4. A process for the production of 3-picoline from a mixture of coal tar bases containing 3-picoline, 4-picoline, and 2,6-lutidine, which comprises fractionating the base mixture to obtain a cut containing substantial proportions of each of the above bases, treating this cut with an amount of hydrogen chloride just sufficient to react substantially completely with the 2,6-lutidine and

4-picoline to precipitate hydrochlorides of these bases, and separating the precipitated hydrochlorides from the residual uncombined base rich in 3-picoline.

5. A process for the production of substantially pure 3-picoline from a mixture of coal tar bases containing 3-picoline, 4-picoline and 2,6-lutidine, which comprises fractionating the base mixture to obtain a cut boiling predominantly in the range of about 140° to 145° C. and containing substantial proportions of each of the above bases, treating this cut, in the substantial absence of water, methanol and ethanol, with an amount of hydrogen chloride just sufficient to react substantially completely with the 2,6-lutidine and 4-picoline to precipitate hydrochlorides of these bases, separating the precipitated hydrochlorides from the residual uncombined base rich in 3-picoline and isolating substantially pure 3-picoline from said residual base in the form of its phosphate.

6. In a process for resolving a mixture containing substantial proportions of 3-picoline, 4-picoline, and 2,6-lutidine, the steps which comprise treating the base mixture with an amount of hydrogen chloride sufficient to react with the major part but not all of the 2,6-lutidine to precipitate substantially pure 2,6-lutidine from such mixture in the form of its hydrochloride, separating the precipitate thus formed, treating the residual uncombined base mixture with an amount of hydrogen chloride substantially equivalent to the 4-picoline and 2,6-lutidine remaining in said base mixture to precipitate these bases from the mixture in the form of their hydrochlorides, and separating the precipitate thus formed from the uncombined base rich in 3-picoline.

7. In a process for resolving a mixture containing substantial proportions of 3-picoline, 4-picoline, and 2,6-lutidine, the steps which comprise treating the base mixture with an amount of hydrogen chloride sufficient to react with the major part but not all of the 2,6-lutidine to precipitate substantially pure 2,6-lutidine from such mixture in the form of its hydrochloride, separating the precipitate thus formed and converting it to free base by treatment with alkali, treating the residual uncombined base mixture with an amount of hydrogen chloride substantially equivalent to the 4-picoline and 2,6-lutidine remaining in said base mixture to precipitate these bases from the mixture in the form of their hydrochlorides, separating the precipitate thus formed from the uncombined base rich in 3-picoline, converting the separated hydrochloride precipitate to free base by treatment with alkali, and treating the uncombined base rich in 3-picoline to separate substantially pure 3-picoline therefrom in the form of its phosphate.

8. A process for resolving into its components a nitrogen base mixture comprising 3-picoline and 4-picoline which comprises reacting said mixture

with hydrogen chloride and forming a reaction mixture containing substantially no water and lower alcohols, whereby 4-picoline hydrochloride is precipitated preferentially to 3-picoline hydrochloride.

- 5 9. A process for resolving into its components a nitrogen base mixture comprising 2,6-lutidine and at least one of the bases 3-picoline and 4-picoline which comprises reacting said mixture with hydrogen chloride and forming a reaction mixture containing substantially no water and lower alcohols, whereby 2,6-lutidine hydrochloride is precipitated preferentially to picoline hydrochloride.
- 10 15. A process for resolving into its components a nitrogen base mixture containing at least two of the bases 2,6-lutidine, 4-picoline and 3-picoline which comprises reacting said mixture with hydrogen chloride and forming a reaction mixture containing substantially no water and lower alcohols, whereby the hydrochloride of at least one of the individual bases in said mixture is precipitated, the order of preference for precipitation of individual base hydrochlorides being the order in which the bases are above named.

- 20 25. 11. In a process for the production of a 3-picoline concentrate from a mixture containing substantial proportions of 2,6-lutidine, 3-picoline and 4-picoline, the steps which comprise reacting said base mixture with an amount of hydrogen chloride just sufficient to react substantially completely with the 2,6-lutidine and 4-picoline, in the presence of a hydrocarbon diluent, to precipitate hydrochlorides of the 2,6-lutidine and the 3-picoline, and separating the uncombined base, enriched in 3-picoline, from said hydrochlorides.
